UNITED STATES PATENT OFFICE

HECTOR P. MACLAGAN, OF OAK PARK, ILLINOIS

DEVICE FOR PRODUCING INFRA-RED RAYS

Application filed March 1, 1926. Serial No. 91,404.

My invention relates to an improved means for producing infra-red rays, intended particularly for therapeutic purposes. While it has been recognized for some time that infra-red rays are helpful and beneficial in connection with various treatments for disorders of the human system, and various means have been proposed for producing these infra-red rays, certain objections have obtained heretofore in connection with the said means proposed. As far as I am aware, these rays have been produced heretofore by employing a heating element of some kind, preferably having some form of an electrical resistance in it, and heating the element by electric current flow sufficiently to emit rays of desired wave length, and projecting the rays directly from the element upon the body to be treated. Practical limitations inherent in electrical heating elements generally, have interfered with the efficient production of infra-red rays in this manner for several reasons, for example it is convenient to have the heating unit in the form of a winding of high resistance wire mounted on an insulated support, to the end that the unit may be compact, and where this is done the heating effect is concentrated in the areas represented by the resistance wire and either one of two effects results, first if it be attempted to produce the infra-red rays in considerable quantity, on account of the relatively small extent of the concentrated areas of production, the wire must be heated considerably above the temperature corresponding to the rays to be delivered from the device and as a result many yellow rays and also rays of shorter wave length are produced, which are known to have a markedly different effect on the body than the infra-red rays, and are therefore not to be desired in connection with infra-red ray treatments, although of course at the same time, infra-red rays are produced in considerable quantity and may be applied to the body being treated, but not without the simultaneous application of the undesirable rays of shorter wave length; on the other hand when such a heating unit is used to develop only sufficient heat to produce the desired infra-red rays, by properly restricting the electric current flow

relatively to the electrical resistance of the heating unit, while the rays produced are of the desired kind, they are produced in such small quantity as to have small effect relatively to the amount of energy being employed to produce them. Again, in using electrical heating units as described, the material of the core of the unit on which the winding is wound, must be selected to meet the requirements for proper insulation, which prevents the selection of the material best adapted to give off infra-red rays in large quantities to the exclusion largely or entirely of rays of shorter wave length, and where the resistance unit is a block or rod of high resistance material, for example a graphite compound, through which the heating current is caused to flow, difficulty is experienced in selecting a suitable material for the block or rod, adapted to give off infra-red rays nearly or quite to the exclusion of rays of shorter wave length.

It is a purpose of my present invention to overcome the defects noted above, by providing the device with a heating unit of some kind, preferably electrically heated, constructed solely from the standpoint of the requirements for producing efficiently the requisite temperature, regardless of the wave length of the rays given off by it, and in connection with such a heating unit, I employ a shell of suitable material surrounding said unit and preferably separated slightly therefrom, to intercept the rays given off by said unit and as a result of the action of said rays upon it, to be heated sufficiently to give off only or principally, infra-red rays. With this construction, the heating unit may be made without regard to its ability to give off infra-red rays, the only requisite being that it shall be capable of producing heat in sufficient quantity to heat the shell to the desired temperature, and at the same time, the material of the shell may be selected to be best adapted to give off only or principally, infra-red rays. A marked advantage secured by this construction is that although the heat developed by the heating unit may be much greater than that required for the production of infra-red rays, and although the heating

effect may be concentrated in relatively limited areas, the shell acts as a diffuser and is heated by the rays given off by the heating element in substantially a uniform manner, and thus by properly making the parts, a relatively large surface of the shell may be heated to the proper temperature for giving off rays limited to the desired wave length or wave lengths. For example, if it is found necessary to limit the rays strictly to infrared rays, this may be done; or if it is desired to limit the rays delivered to red rays, and possibly orange-red rays and rays of longer wave length, where the said red or orange-red rays are not objectionable, this may be done, but in any case the visible rays of short wave length which have markedly different effect on the body treated, from rays of long wave length, may readily be entirely eliminated, even though delivered in considerable quantity from the heating unit.

A broader aspect of my invention consists in the production of a device for the purpose described consisting of a primary source of rays, whether this source be a heating element or otherwise, in the event some means is discovered of producing light and analogous rays by some other means than a heating element, and in conjunction with such primary element, employing a second element intercepting the rays from the primary element and acted upon thereby to produce and give off light rays or rays analogous thereto of long wave length, the material of the second element preferably being selected to effectively produce and give off rays of the desired wave length to the exclusion of waves of shorter wave length.

The above and other objects of my invention and features incidental to the carrying out of my invention, will more fully appear below in connection with the description of the drawings illustrating preferred embodiments of my invention, in which

Fig. 1 shows my device in front elevation,

Fig. 2 shows my device in side elevation,

Fig. 3 shows in enlarged vertical sectional view the ray producing element employed in the device illustrated in Figs. 1 and 2,

Fig. 4 shows in a view similar to Fig. 3 a modified form of ray producing device which is conical instead of cylindrical.

Fig. 5 shows in a view similar to Fig. 3 a further modified form of ray producing device which is spherical instead of being cylindrical, and

Fig. 6 is a diagrammatic side elevation of a modified mounting and supporting arrangement for the ray producing device, affording a different direction of presentation of the ray producing device to the subject, from that indicated in Figs. 1 and 2.

Similar numerals refer to similar parts throughout the several views.

As shown in Figs. 1 and 2, my device con-

sists of a ray producing device indicated at 10 engaged and supported at its lower end by a metal clamping ring 11, which is in turn supported by a metal bracket 12 from a block 13 of insulating material forming the base of the ray producing device. The device 10 is further supported by a second metal bracket 14 engaging the lower end of the central portion of the device 10, this bracket being also supported on the block 13. The brackets 12 and 14 are secured to the block 13 by screws or bolts 15 and 16 respectively, which also engage the ends of wires 17 and 18 by which electric current may be supplied to the device through the brackets 12 and 14.

The structure thus far described is preferably mounted in a reflector 19 of such a conformation, material and inner finish as to direct the rays outwardly from the open end thereof as required in any particular case. The block 13 is secured in place in the reflector 19 by a suitable clamping bolt 20 extending into a handle 21 by which the entire device may be conveniently held. The handle 21 at its outer end is provided with a metal extension 22 to be engaged by any suitable support where it is desired to hold the device in definite relation to the subject treated for an appreciable time. The wires 17 and 18 are preferably led through an insulating bushing 23 in the lower portion of the rear wall of the reflector so that the wires are out of the way of the operator of the device.

The construction of the ray producing device 10 will best be understood by reference to Fig. 3, in which the bracket 14 is shown secured to the lower end of a cylindrical core 24 of insulating, refractory material by a bolt 25 extending through the core and through the upper end of a cylindrical tubular shell 26 supported around the core by said bolt. The lower end of the shell 26 is clamped by the metal ring 11 carried by the bracket 12. The core shown in Fig. 3 carries on its outer surface a winding 27, preferably of high resistance wire, the lower end of which is connected with the bracket 12 as indicated at 28, the upper end of the winding being connected with the bolt 25 as indicated at 29. The shell 26 is preferably closed at its upper end and is of such a length that its lower end is in substantially the same plane as the lower end of the core 24 carrying the winding 27, the inner bore of the shell being preferably somewhat greater than the outer diameter of the core to afford a clearance space between the core and winding, and the inner surface of the shell. The core 24 may be of any insulating material adapted to withstand the heat developed, and to carry the turns of the winding 27 in spaced relation and maintain them so, whether by grooving the core as indicated, or otherwise, as long as the turns of the winding are maintained separated from

each other and electrical connection between them is prevented. I find that lava or porcelain may be used to advantage as the material for the core.

6 The shell 26 may be of any material, whether mineral or metallic, that is adapted when heated to give off infra-red rays. Many different materials may be employed for the shell which may be generally classified as 10 silicates and carbides, for example carborundum and fire clay; in addition carbon, graphite and silicon may be advantageously employed for this purpose, as well as lava and various metals.

15 In Fig. 4, I show a modified construction of ray producing unit 10^a, in which the core 24^a may be of similar material to the core 24, the difference being that the core is conical in shape instead of cylindrical as shown for 20 the core 24, and the core may be similarly wound with a winding 27^a similar to the winding 27 and for the same purpose. The core 24^a has a mounting bolt 25^a extending through it, to which the closed end of a conical shell 26^a is secured, the shell being similar to the shell 26 excepting that it is conical in shape instead of cylindrical, and similarly related to the core and its winding, to the relation above described between the core 24 25 and the shell 26. The open end of the core has a further support comprising a clamping ring 11^a carried by a metal bracket 12^a and the terminals of the winding 27^a are connected with the bolt 25^a and the bracket 30 12^a in a manner similar to that above described. A second bracket 14^a is employed to be engaged by the other end of the bolt 25^a in the manner above described, and as before described, the brackets 12^a and 14^a are intended for mounting on a base of insulating material and serve as the electrical terminals 40 of the heating unit.

45 In Fig. 5, I show at 10^b a further modified form of my ray producing unit in which the core 24^b is in the form of two conical frusta meeting at their larger ends, the core being provided with a winding 27^b similar to the winding 27 above described and for the same purpose. In this construction, the 50 core and its winding is entirely enclosed by the two sections 26^b and 26^c of the shell, each of which is recessed to surround half of the core and its winding, so that these sections 26^b and 26^c together completely enclose the 55 core and its winding. The sections of the shell may be made of the same material as the shell 26 and are similarly related to the core and its winding as far as clearance space is concerned, the outer surfaces of the said 60 sections together constituting a spherical surface. A bolt 25^b extends through the core 24^b and the sections 26^b and 26^c to clamp them together and hold the said parts in proper relative position. A metal clamping ring 11^b 65 surrounds the joint between the sections 26^b

and 26^c, this ring being carried by a bracket 12^b to in part support the unit. A second metal bracket 14^b is secured to the unit by the bolt 25^b to further support the unit and to serve as the other electrical terminal thereof. These brackets are intended for mounting in any desired manner on an insulating base, in substantially the manner indicated in Fig. 1, although it will be understood that I do not restrict myself to any particular relation of the unit to its base and the reflector, since the parts may be held together in any desired relation that will best produce the intended results. As illustrated in Fig. 6 for the unit 10^c, the unit may be mounted with its axis coincident with or parallel to the axis of the reflector, instead of being perpendicular to said axis as illustrated in Figs. 1 and 2. In the construction shown in Fig. 6, the relation indicated is secured by forming the brackets 12^a and 14^a as indicated, the relation of the insulating base 13^a to the reflector, being preferably similar to that described in connection with Figs. 1 and 2.

70 It will be understood that any desired presentation of the outer surface of the shell of the unit to the open end of the reflector may be secured by correspondingly shaping the supporting bracket or brackets of the unit, and mounting the supporting base of the unit in any desired position relatively to the unit and reflector, assuming that the latter is used, that may be most convenient. It will be understood that for some purposes it may not be desirable to have as concentrated an effect 75 as that produced by the use of a reflector, in which case the unit may be used without a reflector.

80 While the material of the shell in any case may widely be selected from the materials described, I find the best results are secured where the material is of such a nature as to be properly designated from the physicist's standpoint, as a "black body," that is a body having such characteristics, at least as to its surface, that all light rays which fall upon it are absorbed, and no light rays of at least 85 visible wave length are given off by it as a result of light that may fall upon its outer surface. It is in this sense that the term "black body" is used in the claims. It will be understood that a body of this kind necessarily, at least as to its surface, has a very high light absorbing value and a very low light reflecting value, and the more closely 90 the material of the shell approaches the requirements of an ideal "black body," the better it will serve its contemplated function in connection with my invention.

95 In the present case, by the term "light rays," is meant rays emanating from a luminous body and having the physical characteristics requisite, at least for certain wave lengths of said rays, to produce the sensation 100 of sight on the eye of a beholder when viewing 105 110 115 120 125 130

objects on which these rays fall, although by the term "light rays" as here used I mean all rays having the general characteristics just stated, whether of a wave length resulting in 5 visible effects, or of too short or too long wave length to produce visible effects.

In using my ray producing device, it is desirable to restrict the shell of the device to such a degree of energization or excitation 10 from the standpoint of ability to give off light rays, that the rays given off will be limited to infra-red rays, or at most to infra-red rays and visible red rays of longer wave length, where the action of the visible red rays on the 15 body treated, is not objectionable, without however, in any case giving off visible light rays of shorter length than orange-red rays or orange rays, since light rays of shorter wave length have been found to have chemical 20 effect on the person treated, as distinguished from the physical effects produced by light rays of longer wave length. The more nearly the material of the shell constitutes an ideal black body, the more effectively 25 these light rays of longer wave length are produced, without the possibility of producing and giving off light rays of shorter and undesirable wave length, as far as the purposes of the present invention are concerned.

30 From a practical standpoint, as far as I am aware, it is desirable to use some form of electrical resistance element as the primary element of my ray producing device, and where this is done, the electrical energy can only be 35 effectively utilized by developing relatively high temperatures in concentrated areas on the element, accompanied, of course, by the production of visible light rays of much shorter length than orange rays. The secondary 40 element of my device serves the double purpose of shielding the person treated from the light rays of relatively short wave length, and at the same time by the heating or excitation by the rays projected against its inner 45 surface by the primary element, the secondary element may conveniently be heated to only the degree required to give off light rays of the desired wave length, with the added advantage that the heated areas of the secondary 50 element or shell, are not concentrated at the outer surface of the shell, but on the other hand, that the material of the shell diffuses the heating effect so that a considerable area or areas of the outer surface of the 55 shell or secondary element are effective in giving off rays of the desired wave length, which are distributed over the surface in substantially a uniform manner, and in this way the energy of the rays given off by the primary 60 element, whether visible or invisible, and whether long or short, is transformed so that this entire energy is effective in producing rays which are given off by the secondary element of no shorter wave length than that 65 desired. In this way practically all of the

energy communicated to the primary element, is delivered from the secondary element in the form of rays of long wave length, without the use of filters or color screens of any kind, so that this entire energy is available for 70 direct application to the person to be treated by means of infra-red rays.

While I have shown my invention in the particular embodiment above described, it will be understood that I do not limit myself 75 to this exact construction as I may employ equivalents known to the art at the time of the filing of this application without departing from the scope of the appended claims.

What I claim is:

1. In an infra-red ray generator, the combination of a core of refractory insulating material, a high temperature resistance wire wound on said core, a shell of material opaque to light rays surrounding said resistance wire 85 and out of contact with it, a rod extending through said core to support it, and means on said rod engaging said shell to support said shell from said rod.

2. In an infra-red ray generator, the combination of a core of refractory insulating material, a high temperature resistance wire wound on said core, a shell of material opaque to light rays surrounding said resistance wire and out of contact therewith but so closely adjacent thereto as to be effectively heated thereby, a rod extending through said core to support it, means on said rod engaging said shell to support said shell from said rod, a first supporting arm engaging said rod, and a second supporting arm holding said shell coaxial with said core.

3. In an infra-red ray generator, the combination of a core of refractory insulating material, a high temperature resistance wire wound on said core, a shell of material opaque to light rays surrounding said resistance wire and out of contact therewith but so closely adjacent thereto as to be effectively heated thereby, a rod extending through said core to support it, means on said rod engaging said shell to support said shell from said rod, a first supporting arm engaging said rod, and a second supporting arm holding said shell coaxial with said core, said supporting arms constituting the electrical terminals of the device.

In witness whereof, I hereunto subscribe my name this 24th day of February, A. D. 1926.

HECTOR P. MACLAGAN.
